UNITED STATES PATENT OFFICE.

LOUIS BALLBACH, OF DETROIT, MICHIGAN.

LACING-EYE FOR SHOES, &c.

SPECIFICATION forming part of Letters Patent No. 706,218, dated August 5, 1902.

Application filed December 7, 1900. Serial No. 38,991. (No model.)

To all whom it may concern:

Be it known that I, LOUIS BALLBACH, a citizen of the United States of America, residing at Detroit, in the county of Wayne and State 5 of Michigan, have invented certain new and useful Improvements in Lacing-Eyes for Shoes, &c., of which the following is a specification, reference being had therein to the accompanying drawings.

10 This invention relates more specifically to a combined hook and eyelet, whereby in lacing a boot, a shoe, or other object one lace-string may be passed through the eyelet and the other engaged with the hook.

15 The object of the invention is to produce a clamping action on the lace-strings, so that some portion may be laced tighter than any other portion; and to this end the invention consists in a combined lacing hook and eye- 20 let, so arranged that the hook and eyelet together perform the function of a clamp, all as more fully hereinafter described, and shown in the annexed drawings, in which—

25 Figure 1 is a perspective view of a shoe to which my improved lacing-hook is applied. Fig. 2 is a cross-section on line *x x*, Fig. 1. Fig. 3 is a detached perspective view of the lacing-hook with the parts thereof shown detached. Fig. 4 is a similar detached perspective of a modified construction of said lacing-hook. Fig. 5 is a section through the modified form of lacing-hook represented in Fig. 4.

30 My improved lacing-hook consists of the eyelet portion *a*, formed with the usual head and shank, and of the hook portion *b*. The latter is formed with hinge-pintles *c*, and the head of the eyelet is correspondingly provided with eyes *d*, adapted to receive the pintles, and thereby form a hinge-joint connection 35 40 when the parts are secured between the eyelet and the hook in such a manner that the hook is adapted to close down over the eye in the eyelet, as shown in section in Fig. 2.

45 Fig. 1 shows how the device is intended to be used on shoes. In this figure, *e* indicates the usual eyelets, of which there is usually a double row of five or six. *f* indicates a like double row of the usual hooks, and *g* indicates two lacing-hooks of my invention. It 50 will thus be seen that my lacing-hook is placed in lieu of the last two eyelets adjacent to the hooks *f*.

The manner of securing my lacing-hooks is by fastening the eyelets thereof, together with the hooks, in position the same as is done with 55 the ordinary eyelets, all in such manner that the hooks are in position to receive the lacing-strings the same as the other hooks *f*. In lacing the shoe the two ends *A A* of the lace-string are passed through the eyelet portions 60 of my device the same as they have already been laced through the ordinary eyelets *e*; but instead of passing on to the hooks *f*, as in the ordinary way of lacing, each end of the lace-string is first passed around the hook 65 portion of the opposite device, after which the lacing is then completed as in the ordinary manner. In doing so it will be seen the tension with which the lace-string pulls on the hooks *b* will press down said hooks upon the 70 eyelets to which they are hinged, and thereby clamping the lace-string where it passes between them.

In lacing shoes it is always desirable to lace them less tightly on the ankle than on the instep, as tight lacing on the ankle stops the circulation of the blood and tires the foot, while on the other hand tight lacing over the instep supports the foot and assists it in walking and at the same time makes the foot look 80 trim and neat. If the ordinary lacing hooks and eyelets *f e* only are used, the lacing cannot be done in this manner, as the loose and tight portions soon equalize their tension and the strings become loose over the instep and 85 tighten around the ankle. My improved lacing-hooks prevent this, as the clamping action of the hook portions prevents the strings from slipping through the eyelet portion. At the same time there is no more trouble in lacing 90 or unlacing the shoes than there would be without the use of my device.

From this description and illustration the application of my invention to other articles of wearing-apparel where a similar result may 95 be desired is now evident and need not be further described.

As shown in the drawings, the bearings *d* need not be perfectly closed, as the hook will be prevented from disengagement by the fabric when the eyelet is secured in place. Various modifications in the construction of the device may be made without affecting the spirit of my invention, which consists in so

combining the hook and eyelet portions that they form a clamping-jaw. Such clamping action is obtained by hinging the hook in a plane parallel to and below the face of the 5 eyelet, as shown in the drawings.

The hook may be formed in any suitable manner that will cause it to act as a lever in pressing down upon the lace-string in the eyelet by the tension of the lace-string engaged 10 with the hook, and if desired a hump may be formed at *h* on the under side of the hook to press down upon the eyelet or enter into and wedge the lace-string fast in the eye of the eyelet.

15 It is obvious that the hook may be particularly connected to the eyelet in any manner that will permit of moving it out of the way when passing the lace-string through the eyelet.

20 Figs. 4 and 5 show a modified construction in which the hook is formed of wire and hinged to a washer *i*. A common eyelet *j* is then used in connection with it to make the device complete and fasten it to the fabric.

25 What I claim as my invention is—

1. A lacing-hook consisting of an eyelet having means for fastening it to the garment, and a hook formed with a shank hinge-connected at one end to the eyelet in a plane parallel to 30 and below the plane of the face of the eyelet and adapted to bear against the face of the eyelet at or near its opposite end, said end having an outwardly-turned hook portion

forming an open inlet into the hook above the shank portion whereby the lacing-string may 35 be engaged into the hook when the hook is folded down upon the eyelet and produce a clamping action between the shank and the eyelet to prevent another portion of the lacing-string drawn through the eyelet itself 40 from being drawn through the eyelet, by the tension of that portion of the lacing-string engaged with the hook.

2. A lacing-hook consisting of an eyelet having means for securing it to the fabric, and 45 a hook formed with a shank hinge-connected at one end to the eyelet in a plane parallel to and below the plane of the face of the eyelet and provided upon its under side with a bearing portion adapted to project into the eyelet, 50 the free end of the shank having an outwardly-turned hook portion forming an open inlet into the hook above the shank portion, whereby the lacing-string may be engaged into the open mouth of the hook when the hook is folded 55 down upon the eyelet and thereby produce a clamping action upon another portion of the lacing-string drawn through the eyelet itself.

In testimony whereof I affix my signature 60 in presence of two witnesses.

LOUIS BALLBACH.
